UNITED STATES PATENT OFFICE.

CHRISTOPHER WALLER PANK, OF CHICAGO, ILLINOIS, ASSIGNOR TO THE
E. & T. FAIRBANKS & COMPANY, OF ST. JOHNSBURY, VERMONT.

DESIGN FOR A DIAL-FACE.

SPECIFICATION forming part of Design No. 31,673, dated October 17, 1899.

Application filed September 1, 1899. Serial No. 729,260. Term of patent 14 years.

To all whom it may concern:

Be it known that I, CHRISTOPHER WALLER PANK, a citizen of the United States, residing at Chicago, in the county of Cook, State of Illinois, have invented a certain new and original Design for a Dial-Face for Weighing-Scales, of which the following is a description, reference being had to the accompanying drawing and to the letters of reference marked thereon.

My invention relates to a new and original design for a dial-face for weighing-scales; and the leading feature of the design consists in a dial-face having arranged upon it systems of lines and blocks, as indicated in the accompanying drawing, in which the figure represents a front elevation of the dial-face embodying my design.

In the drawing, A represents as a whole the face of the dial provided with the short radial

lines *a* *b* and the series of dark blocks *c*, with light blocks *d* alternating therewith, the radial lines *b* being arranged in the center of each light block between two dark blocks. The lower ends of the short radial lines *a* are all connected by a circular line *e*.

The essential part of the design is the alternating light and dark blocks arranged upon the face of the dial.

Having thus described my invention, what I claim, and desire to secure by Letters Patent, is—

The design for a dial-face, substantially as shown and described.

In testimony whereof I affix my signature in presence of two witnesses.

CHRISTOPHER WALLER PANK.
